B. Hotchkiss,

Drop Hammer,

No 41,775.

Patented Mar. 1, 1861.

Rufus Stanford.

UNITED STATES PATENT OFFICE.

BENNET HOTCHKISS, OF NEW HAVEN, CONNECTICUT.

IMPROVEMENT IN DROP-HAMMERS.

Specification forming part of Letters Patent No. 41,775, dated March 1, 1864.

To all whom it may concern:

Be it known that I, BENNET HOTCHKISS, of New Haven, in the county of New Haven and State of Connecticut, have invented new and useful Improvements in Drop-Lifters; and I do hereby declare the following to be a full, clear, and exact description of the construction and operation of the same when taken in connection with the accompanying drawings and the letters of reference marked thereon, and which said drawings constitute part of this specification, and represent, in—

Figure 1, a front view of a drop press with my lifter attached; Fig. 2, a sectional view of the lifter; Figs. 3 and 4 and 5 are detached views to illustrate the operation.

Similar letters and characters indicate like parts in the several figures.

To enable others skilled in the art to make and use my invention, I will proceed to describe its construction and operation.

A is the anvil block or base, and supports the hammer B and its operative mechanism. The upper part, C, is constructed so as to form guides c c, to receive and guide the hammer B.

D is the driving-shaft supported in proper bearings, G G. E is the driving-pulley fixed to the driving-shaft D, through which to apply power to operate the machinery of the lifter.

F is a cylinder, fitted so as to turn freely on the shaft D. Its two heads a and e are of a conical form, as seen in section, Fig. 2. Fixed to the shaft D (or a part of it) is a disk or head, H. Its inner surface must be the reverse in form, and made to fit the head a of the cylinder F. Another similar disk or head, I, is placed upon the shaft D and loose thereon, its inner surface made to fit the head e of the cylinder F.

d is a spindle, inserted into the end of the driving-shaft, and to the inner end of the said spindle is fixed a block, f. This spindle and block have a lateral movement independent of the shaft D, the block f moving in a slot made in the shaft for the purpose. The block f must be of sufficient length to project through the shaft, as shown in Figs. 1 and 2, to act upon the head or disk I.

L is a lever, has its fulcrum at g, and hung so that its shorter arm, a', may act upon the spindle d. When power is applied to the longer arm, a², of the lever L to bring the said

arm down and lock it under the latch O, (see Figs. 1 and 3,) the shorter arm will press the spindle d and the block f, attached thereto, inward, and by this operation the block f will force the head or disk I against the cylinder F and firmly clamp the said cylinder between the two heads I and H, and the friction thus produced will cause the cylinder F to revolve with the driving-shaft.

N is a flexible strap or band, one end fixed to the hammer B, the other end made fast to the cylinder F, so that when the said cylinder is revolved in the manner described it will wind up the strap N and draw up the hammer from the anvil. As soon as the power which holds the head I against the cylinder F is removed, the cylinder is freed from the action of the driving-shaft. Thus free, the hammer will fall upon the anvil, (or work thereon,) unwinding the strap from the cylinder in its descent, and will remain down until the cylinder is again clamped as before between the two heads.

I operate the lever I to clamp the cylinder in the following manner: P is a rod, which has a vertical movement. On the upper end of the said rod I form a hook or catch, R, represented in Figs. 2 and 4 as raised and in Figs. 1 and 3 as down. The said hook or catch acts upon the longer arm of the lever L, so that as the said rod is drawn down from the position in Figs. 2 and 4 to that shown in Figs. 1 and 3 it will force the lever L from the position in Figs. 2 and 4 to that shown in Figs. 1 and 3. In this operation the lever L will force the spindle d in for the purpose before fully described, and when the lever is drawn down sufficiently far a latch, O, (see Fig. 3,) will latch onto the end of the lever L, and will hold the cylinder clamped until the said lever is released from the latch. This enables me to give an instantaneous release to the hammer, which allows the hammer to fall from its highest elevation with the unretarded force of its full weight. To produce this instantaneous release I latch the lever, as before described. On the rod P, I form an inclined plane, R', (see Figs. 3 and 4,) and on the latch O and above the said inclined plane I make a projection, r, so that when the rod P is raised, as in Fig. 4, the inclined plane will strike the projection and force the latch back to release the lever L, and when so released the action of the spring u raises

the longer arm of the lever L and instantly releases the clutch; as in Fig. 2, and the hammer falls unretarded. The rod P may be raised and drawn down by the foot or hand of the operator; but such an operation would be inconvenient and troublesome.

In Fig. 5 I illustrate my device for an automatic operation. 2 is a plate moving freely up and down upon a projecting guide, *c'*, on the frame C. 3 is a stop on the frame C below the plate 2. This stop should be adjustable, so as to be set higher or lower, as occasion may require, for the purpose of fixing a point below which the said plate cannot fall. Pivoted to the said plate are levers 5, 6, and 7. To 5 and 6 springs are applied to act to raise the longer end of 5 and to force 6 toward the hammer B, as represented in Fig. 1. The lever 5 is represented in blue, Fig. 5, and in red as drawn down by means of the cord or rod 8, attached to a treadle, 15. (See Fig. 1.) The lever 6 is represented as free, and by the action of the spring is forced inward toward the hammer into such position that as the hammer is raised it will strike the end of the lever 6. (See hammer in red, Fig. 1.) The hammer, still ascending, will carry with it the plate 2 until the said lever 6 is drawn away by means of the cord or rod P in the hands of the operator, as shown in red, Fig. 1. The hammer will then strike the longer arm of the lever 7 (see in blue Fig. 1) and turn the shorter arm up to clamp and hold firmly the rod P, as shown in red Fig. 5. The hammer still ascends and now raises with it the rod P. The result of thus raising the rod is to release the clamp, as described, and illustrated in Figs. 2, 3, and 4, and allow the hammer to drop. As the hammer descends the plate also descends of its own weight to rest on the stop 3. The rod P, now released from the lever 7, through the action of which it was raised, might of its own weight draw the clamp again into action to raise the hammer or very much retard its descent. To avoid such a result, I fix upon the frame a latch, 11. (See Fig. 1.) As the rod P reaches its full height the latch 11 will by the action of the spring 12 spring into the notch 13 in the rod P and hold up the rod until the hammer shall have descended so far as to strike the latch, which projects inward under the hammer, as seen in red Fig. 1, and force it (the latch) out of the notch 13. Then the projection *s* from the hammer will strike the projection *s'* on the rod and draw the rod down to engage the clutch to raise the hammer again, and at whatever point in its ascent the hammer is allowed to strike the lever 7, as described, it (the hammer) will be released and fall. That point is at the option of the operator, it being at such point as he may choose to draw the lever 6 away, so as to allow the hammer to pass it.

Should it be desirable to arrest the descent of the hammer or hold it suspended, the lever 5 is allowed to spring in from the position shown in red Fig. 5 to that shown in blue Fig. 5.

On the guide *c'*, I make notches, (see Figs. 1 and 5,) and within the slide-plate 2, I hang a latch, 16, (see Fig. 5,) upon a pivot, 17, and connect the latch with lever 5 by a projection, 18, through the plate, and, as the hammer descends, it will catch upon the said lever 5, as shown in broken lines Fig. 1, and cause the latch 16 to catch into one of the notches (see Fig. 5) and hold the slide up. This will sustain the hammer, and may be held in any position desired by the operator. To release the hammer from such suspension, the operator draws upon the cord or rod 8 to remove the lever 5 back to the position denoted in red, Fig. 5, and unlatch the slide, when both the hammer and slide will fall.

The machine which I have thus described is substantially the same as one of those referred to in my affidavit filed in the Patent Office on about the 30th day of November, 1862, relating to the testimony taken in the case of interference declared, October 17, 1862, by the Honorable Commissioner of Patents, between my application for a patent for improvement in drop-presses and the patent of William F. Goulding and Frank Cheney, granted September 16, 1862, and in which case the Honorable Commissioner issued Letters Patent to me bearing date of February 17, 1863.

Having thus fully described my invention, what I claim thereon as new and useful, and desire to secure by Letters Patent, is—

1. The friction-clutch described, in combination with the hammer of drop-presses when the same is constructed and operated in the manner and for the purposes substantially as herein set forth.

2. The lever L and spindle *d*, when the same are combined with the friction-clutch described, for the purpose specified.

3. The combination of the rod P and latch O with the lever L in the manner and for the purpose substantially as described.

4. The levers 6 and 7, when combined with the hammer of drop-presses, in the manner and for the purpose specified.

5. The lever 5 and latch 16, when combined with the hammer of drop-presses, substantially as described.

6. The latch 11, in combination with the rod P and the hammer of drop-presses, substantially in the manner described.

BENNET HOTCHKISS.
